UNITED STATES PATENT OFFICE.

JOSE M. ESPINOSA, OF SAN FRANCISCO, CALIFORNIA, ASSIGNOR TO
WILLIAM DAVIS, OF SAME PLACE.

DESIGN FOR A CHEEK OR SIDE PIECE FOR BRIDLE-BITS.

SPECIFICATION forming part of Design No. 16,521, dated February 16, 1886.

Application filed December 23, 1885. Serial No. 186,581. Term of patent 7 years.

To all whom it may concern:

Be it known that I, JOSE M. ESPINOSA, a citizen of Mexico, residing at the city and county of San Francisco, and State of California, have invented a new and original Design 5 for the Cheek or Side Pieces for Riding or Driving Bridle-Bits, of which the following is a specification, reference being made to the accompanying drawings, forming a part thereof.

10 Figure 1 is a perspective view of a bridle-bit, showing my design for the cheek or side pieces. Fig. 2 is a side elevation of the bit, showing more clearly the design of the cheek or side piece.

15 This invention relates to a design for the cheek or side pieces of a bit, the essential feature of which is the figure of a running or rearing horse having rings or loops *a a'* formed integral therewith, as shown. The 20 outer surface of the piece A has lines of ornamentation upon it, indicating or delineating the various features of a horse, such as the eye, nostril, mouth, mane, &c. The ring or loop *a* is on the upper portion of the neck of 25 the horse, while the ring, loop, or swivel and

chain *a'* is at the extremity of the hind feet. The horse may be turned either forward or back. It is best, perhaps, to extend the feet to the front, to prevent them from interfering with or chafing the cheeks or mouth of the 30 animal.

Having thus described my design, what I claim as new, and desire to secure by Letters Patent, is—

In a design for a cheek or side piece, the 35 side piece, A, in the form and outlines of a horse shown in a rearing or extended position, as in running, and having the parts *a a'* and suitable delineations or lines of ornamentation upon its surface, indicating the facial 40 characteristics, the mane, and other features of the horse, substantially as herein shown and described.

In witness whereof I have hereunto set my hand.

J. M. ESPINOSA.
